SHOE AND THE LIKE

Leo Thomas John Dack, Leicester, England

Application August 30, 1944, Serial No. 551,797
In Great Britain July 26, 1943

11 Claims.

(Cl. 36—2.5)

This invention concerns boots, shoes, slippers and like articles of footwear hereinafter, for convenience, referred to broadly as shoes. It is one object of the invention to provide a construction of heel that, on the one hand, is resilient and is therefore comfortable to the wearer and that, on the other hand, affords considerable scope in the design and construction of fashion shoes.

According to this invention a shoe has the heel seat supported upon at least one spring so located beneath the heel as to be placed under bending stress by the weight of the wearer.

As viewed from another aspect the invention provides a shoe having a spring heel constituted by at least one rod-like spring extending in the general direction of the length of the foot between a heel seat and a part that makes contact with the ground so as to be placed under bending stress by the weight of the wearer.

The invention further includes a shoe having the heel constituted by at least one C-spring or its equivalent and having the heel seat constituted by or attached to the top bar of the spring. Springs that, for the purpose of this invention are the equivalent of a C-spring, include a U-shaped or other forked spring placed on its side in a vertical plane so as to provide one top bar and one bottom bar and a bend or union between the two bars that is adapted to flex when the weight of the wearer of the shoe is applied to the top bar and the bottom bar rests, directly or indirectly, on the ground, an S-spring, and a ring-like or oval spring. The resilience, and the scope in fashion designing, afforded by such a heel will readily be appreciated by those concerned with the art.

Preferably, but not necessarily, the lower part or bar of the heel spring or springs is attached to a plate (e. g. of metal) or other connection that extends forward therefrom to the ball of the foot and is there flexibly connected to a member of the shoe sole. In the case of a single spring, the heel seat may be constituted by the broad upper bar of the spring if the latter is of sheet material, or may be constituted by a platform attached to the upper bar. Preferably, however, the heel is constituted by two springs, one at each side, and the heel seat is constituted by a platform extending across between the tops of the springs.

The foregoing and other features of the invention set out in the appended claims are incorporated in the constructions now to be described as examples, with reference to the accompanying drawings, in which—

Figure 1 is a perspective view of one shoe and Figure 2 is a side elevation illustrating certain details thereof;

Figure 3 is a perspective view of another shoe and

Figure 4 is a perspective view of the spring heel thereof;

Figures 5 and 6 are views corresponding to Figs. 3 and 4 of another shoe and heel;

Figures 7 and 8 corresponding views of a still further shoe and heel;

Figures 9 and 10 are perspective views of further shoes.

In one construction according to this invention Figs. 1 and 2, the open heel comprises two C-springs 1 located in parallel vertical planes, having substantially straight and substantially parallel top and bottom bars 1a, 1b respectively, directed towards the rear with a single curved position joining the two bars of each spring. These springs are of metal (preferably tubular) such for example as stainless steel or chromium plated metal. Between the bottom bars 1b, the rear end of a metal plate 2 is secured; this plate extends forwards and at its front end is hinged or otherwise flexibly connected in the region 3 of the ball of the foot to the rear edge of the shoe sole 4. To effect this connection, the sole and plate may be formed with intermeshing rebates and riveted together. A leather or equivalent top piece 5 is fixed to said plate 2 beneath the heel, preferably by means of a readily-releasable fastening or clip that permits of the rapid replacement of a worn top piece.

The heel seat comprises a platform 6 that extends across between the top bars 1a of the two springs. This platform is attached to the sides of the heel or counter 7 and is suitably reinforced, and at each side the counter is provided with a suitable loop or tunnel 8 that encloses the top bar 1a. The heel of the shoe may be open at the rear except for a strap, ribbon or the like 9.

In the foregoing construction the shoe is void of any sole member extending, beneath the instep, up from the ball of the foot to the heel seat and the sides of the upper may be severely cut away in the region of the instep as at 10.

Figures 3 and 4 illustrate the fact that the complete spring heel can be affixed to an ordinary welded (stuck-on), machine-sewn, or welted sole 11 through the medium of the top plate or platform 12, (the equivalent of plate 6, Fig. 1) and fixing screws 14. The plate 12 is fixed to the C-spring 13, the shape of which differs from

that of spring 1. Fig. 5 shows a shoe (e. g. a man's shoe) having a sole 15 of normal construction attached to the C-spring 16 by a plate 12, Fig. 6, but as illustrated in Fig. 9, the sole member may be attached to the top bars of the 5 spring by loops 8.

The heel shown in Figs. 5 and 6 is comparatively low, the top and bottom bars being close together.

The top bars of the C-spring and/or the metal or other heel seat platform that spans said bars may extend forward beneath the instep to the ball of the foot. This is illustrated in Figs. 7 and 8, which show the application of the invention to a high-heel model, wherein the spring 17 has forwardly and downwardly-curving top bars 17a, spanned by a plate 18 provided with attachment means 14 for the sole.

A wedge heel effect may be achieved as illustrated in Figs. 9 and 10. In the former, the top platform 20 extends down beneath the instep and converges to and joins a bottom platform 21 fixed to the bottom bars of spring 19, and extending forwards therefrom. In the modification shown in Fig. 10, the sole 22 is split at the rear, as far forward as the ball, into upper and lower layers 22a, 22b. The upper layer 22a rests on and is secured to plate 20, and the lower layer 22b underlies and is secured to plate 21.

It will be appreciated that in all of the foregoing constructions the springs extend in the general direction of the length of the foot and at least the bends or elbows thereof are placed under bending stress by the weight of the wearer.

I claim:

1. A shoe or similar article, having an upper, a heel seat, and an open spring heel consisting of a pair of exposed rod-like C-springs extending in the general direction of the length of the foot beneath the seat, for supporting the latter and the weight of the wearer so as to be placed under bending stress by said weight.

2. A shoe or similar article, having an upper, an open spring heel comprising a pair of bent rod-like springs whereof each has an upper and a lower bar extending in the general direction of the length of the foot and a curved portion joining said upper and lower bars, and a heel seat platform extending across between and attached to said two upper bars.

3. A shoe or similar article, having an upper, an open spring heel comprising a pair of bent rod-like springs whereof each has an upper and a lower bar extending in the general direction of the length of the foot and a curved portion join-

ing said upper and lower bars, and a heel seat constituted by a platform extending across between the two top bars and having side tunnels in which they are received.

4. A shoe or the like according to claim 2, incorporating a sole member extending forward from the two lower bars to the region of the ball of the foot.

5. A shoe or similar article having an upper, 10 and an open spring heel comprising a pair of rod-like springs spaced side-by-side and extending in the general direction of the length of the foot.

6. A shoe or similar article, having an upper, 15 and an open spring heel comprising a pair of rod-like springs located side by side and each including a top bar that curves forward and downwards beneath the instep to the ball of the foot.

7. In a shoe or similar article an open spring heel consisting of two rod-like spring members 20 located side by side and each having a top bar and a bottom bar connected thereto by an integral flexible portion, said top and bottom bars extending in the general direction of the length of the foot, and a heel seat attached to the two top bars.

8. A shoe or similar article comprising a sole, 25 an upper lasted thereto, an open spring heel consisting of a plurality of curved springs spaced apart across the width of the shoe and each including a top bar extending in the general direction of the length of the shoe, and means attaching the sole to the top bars.

9. A shoe or similar article according to claim 2, having in combination a sole member, a metal 30 plate secured to the two bottom bars and extending forward to the region of the ball of the foot, and means flexibly connecting the plate to the sole member at said region.

10. A shoe or similar article, comprising an 40 upper, an open spring heel attached thereto and comprising a plurality of rod-like springs located side by side and each comprising top and bottom bars extending in the general direction of the length of the foot and a bend joining them, a top platform attached to the top bars and extending forward and downwards beneath the instep to join the bottom platform herein recited, and a bottom platform attached to the bottom bars and extending forward to join the top platform.

11. In a shoe or similar article according to 45 claim 10, a sole member split at the rear into upper and lower layers whereof the upper layer rests on the top platform and the lower layer underlies the bottom platform.

LEO THOMAS JOHN DACK.
